C. J. FANCHER

BOX

Filed Dec. 11, 1926

INVENTOR.
Charles J. Fancher,
BY
Frank A. Cutler,
ATTORNEY.

UNITED STATES PATENT OFFICE.

CHARLES J. FANCHER, OF WINDSOR, VERMONT, ASSIGNOR TO THE HUBBARD CORPORATION, OF WINDSOR, VERMONT, A CORPORATION OF VERMONT.

BOX

Application filed December 11, 1926. Serial No. 154,120.

My invention relates to improvements in telescoping receptacles, containers, or boxes, usually made of pasteboard or more or less similar material, and consists essentially of 5 an open-ended body having an articulated side that can be opened and closed, and an open-ended, slip-on cover, all as hereinafter set forth.

The primary object of my invention is to 10 produce a box which is specially adapted for receiving and containing glaziers' points, since said box is capable of having such points packed therein by the machine that produces glaziers' points and forms them 15 into lengths, stacks, or piles, commonly known as "sticks", and of enabling the points therein to be conveniently removed therefrom, stick by stick, without liability otherwise of disarranging the contents of the box. 20 In the manufacture of glaziers' points, said points are, with the aid of adhesive material, formed into sticks each of which usually includes one hundred points, and it is customary to pack these sticks in boxes, 25 with the sticks arranged in five rows of ten sticks to a row, the rows being separated by pieces of pasteboard, and this box is especially well adapted for so packing glaziers' point sticks therein. The sticks are generally 30 removed from the box one stick at a time, and here again this box is especially valuable, because of the facility afforded by the same in removing the sticks therefrom, such removal being possible without disarranging the sticks which remain in the box. 35 Heretofore it has been necessary to remove the sticks endwise, instead of sideways as in the present case, through the open end of the box, with resulting disarrangement and 40 breakage of the sticks and separation of the points. Besides, the old method of removal is inconvenient.

The box when packed can be kept closed and the contents thereof retained in practically its original and normal condition, except when it is necessary to open the box for the removal of a stick of points. Inasmuch as these sticks of points are usually transferred from the box to a glaziers' point

driver designed to receive unbroken sticks it 50 is quite obvious that much time, labor, and a greater or less number of points are wasted in the event said sticks become broken and the points become separated from each other and loose in the box, a condition very 55 liable to obtain when sticks are packed in an ordinary box.

Although my box is designed more especially for receiving and holding glaziers' points, it might be utilized for receiving 60 and holding other objects.

Other objects and advantages will appear in the course of the following description.

I attain the objects and secure the advantages of my invention by the means illustrated in the accompanying drawings, in 65 which—

Figure 1 is an isometric view of the body of a box which embodies a practical form of my invention, showing the same packed 70 with its full complement of five thousand glaziers' points in sticks, and the loose side or lid raised; Fig. 2, an isometric view of the cover of said box; Fig. 3, an isometric view of said box complete, but with said 75 cover partially withdrawn from said body; Fig. 4, an isometric view of a box body provided with a modified form of closure for the open side thereof, and, Fig. 5, an isometric view of a box body provided with still 80 another modified closure for the open side thereof.

Similar reference characters designate similar parts throughout the several views.

In Fig. 1 is represented a quantity of glaziers' points 1, assumedly five thousand points in all, said quantity being divided 85 and formed into fifty sticks 2 arranged in rows of ten sticks in each row, which, with four separators 3 between said rows, make 90 up the contents of the box illustrated in connection herewith. It is to be understood, however, that similar boxes may be proportioned to contain more or less than the aforesaid number of points, sticks, and rows, and 95 separators, differently arranged, and also made to contain objects other than glaziers' points.

Although the box preferably and as illustrated is oblong in plan, the same might, of course, be square in plan.

The preferred form of the box body, which is that illustrated in Figs. 1 and 3, consists of an end or bottom piece 4, the body being open at the opposite end or top, oppositely-disposed narrow side pieces 5, and oppositely-disposed wide side pieces 6 10 and 7. The side pieces 5 at their bottom edges are affixed to the ends of the bottom piece 4, and the side piece 6 at its bottom edge is affixed to one of the longitudinal edges of said bottom piece and at each of 15 its longitudinal edges to one longitudinal edge of each of said first-named pieces. The side piece 7 is of the same area as the side piece 6, has its bottom edge articulated at 8 to the longitudinal edge of the bottom 20 piece 4, which last-named edge is opposite to that to which the side piece 6 is affixed. Thus it is seen that the side piece 7, when closed, forms junctions with the longitudinal edges of the side pieces 5, which edges 25 are opposite to those to which the side piece 6 is affixed, but that said first-named side piece can be swung upwardly or outwardly on the articulation 8, as shown in Fig. 1, when access to the interior of the body may 30 be had through one side as well as through the bottom end thereof.

A slip-on cover 9 is provided for the body described above. The cover 9, which is open at the bottom, is of the usual construction of covers of this type.

When access to the body is to be had by opening the side piece 7, said body is usually held or placed with the side piece 6 underneath in order that said first-named side 40 piece can be opened upwardly, wherefore said first-named side piece may be termed the lid of the body.

Ordinarily the cover 9 is slipped onto the body only when the side piece or lid 7 is closed, as shown in Fig. 3.

To fill this box with the glaziers' points 1 in accordance with the usual custom, the box body is placed in the point-making machine, with the lid 7 in a vertical position, and 50 sticks 2 of said points with the separators 3 are fed and placed in said body until the same is full; then the body is removed from the machine, said lid is closed onto the free longitudinal edges of the side pieces 5, over 55 said points, and the cover 9 is slipped onto the body over the open end thereof, thus holding said lid in closed position and preventing said sticks from falling out of the open end of the body. Upon removing the 60 cover 9 and opening the lid 7 access is had to the body for the convenient removal of the sticks 2. If the lid 7 be closed and the cover 9 placed on the body, after removing one or more of the sticks 2 each time, the sticks remaining in the body are retained, with the

exercise of little care, in their original positions, so that liability of the breaking up of the sticks and the separating of the points from their sticks is greatly reduced and may be avoided altogether.

In Fig. 4, in place of the lid 7 are two lids 10 each of which has one longitudinal edge articulated at 11 to the longitudinal edge of one of the narrow side pieces 5, which last-named edge is opposite to that to which one 75 longitudinal edge of the side piece 6 is affixed. Otherwise the construction of this box body is similar to the first one. The lids 10 are of equal width so that their free longitudinal edges ~~about~~ when said lids are 80 closed. When this box body rests on its side piece 6, the lids 10 open upwardly in opposite directions. When the lids 10 are closed two of their short edges ~~about~~ the longitudinal edge of the bottom piece 4, which 85 last-named edge is opposite to that to which one edge of the side piece 6 is affixed. The cover 9 is applicable to this body, and also to the body illustrated in Fig. 5, as well as to the body herein first described.

In Fig. 5 appears a body similar to that shown in the first two views, except that it has a lid 12 which has one longitudinal edge articulated at 13 to the longitudinal edge of one of the narrow side pieces 5, which last-named edge is opposite to that to which one longitudinal edge of the side piece 6 is affixed. When the lid 12 is closed, the free longitudinal edge thereof and one of its transverse edges respectively ~~about~~ the free longitudinal edge of the narrow side piece 5 that is opposite to the narrow side piece 5 with which said lid is articulated, and the free longitudinal edge of the bottom piece 4. The lid 12 opens upwardly or outwardly on 105 one of the side pieces 5, instead of on the bottom piece 4 as in the first case.

Minor changes in the shape, size, construction, and arrangement of some or all of the parts of this box, in addition to those hereinbefore specifically pointed out, may be made without departing from the nature of my invention, or exceeding the scope of what is claimed.

What I claim as my invention, and desire to secure by Letters Patent, is—

1. The combination, in a box, a body comprising an end piece, three side pieces permanently attached to said end piece and to each other, and a side piece articulated to said end piece and adapted when closed to form the fourth side of said body, all of said side pieces being approximately of the same length, and the body opening only through one end when said articulated side piece is closed, of a telescoping cover, open at one end and closed at the other, fitting said body outside of all of said side pieces, and closing with its closed end the open end of said body.

2. The combination, in a box, with a body comprising a bottom piece, three side pieces permanently attached to said bottom piece and to each other, and a cover piece articulated to one of said fixed side pieces, of approximately the same area as the opposite fixed side piece, whereby is formed, when said cover piece is closed, a body open only at one end and having an uninterrupted clear space within the confines of said body, side, and cover pieces, of a slip-on cover closed at one end and open at the other, and adapted to close the open end of said body and retain said articulated cover piece in closed position against the free edges of said fixed side pieces.

CHARLES J. FANCHER.
